(57) **CLAIM**

The ornamental design for a key configuration for a keyboard, as shown and described.

DESCRIPTION

FIG. 1 is a top view of a key configuration for a keyboard showing our new design;

FIG. 2 is a perspective view thereof;

FIG. 3 is a front view thereof, the rear view being a mirror image thereof;

FIG. 4 is a right side view thereof, the left side view thereof being a mirror image thereof; and,

FIG. 5 is a top plan view similar to FIG. 1 showing the key configuration on a first exemplary keyboard.

The broken line showing of the boundary of the claimed key configuration region and the remainder of an exemplary keyboard in FIG. 5 is for illustrative purposes only and forms no part of the claimed design.
